WASHING-MACHINE.

1,294,682.

Specification of Letters Patent. Patented Feb. 18, 1919.

Application filed January 31, 1918. Serial No. 214,735.

To all whom it may concern:

Be it known that I, WILLARD S. LILLIBRIDGE, a citizen of the United States, residing at Elk City, in the county of Montgomery and State of Kansas, have invented 5 certain new and useful Improvements in Washing-Machines, of which the following is a specification.

This invention relates to washing machines, and more especially to those which are intended to cleanse clothing by means of gasoline or other liquid washer; and the object of the same is to produce an apparatus of this character in which the clothes 15 may be dipped in the gasoline repeatedly, may be held submerged as long as desired, and may be raised above the gasoline and rotated so as to air them, when the cleaning process is completed.

20 A further object is to produce an apparatus of this character which is simple in its structure and therefore may be cheaply manufactured and easily maintained in operative condition, and wherein the air is admitted at the top and is extracted from the side and carried to a point exterior of the building so that odors are avoided and the danger of a conflagration is reduced to a minimum.

25 These and other objects are carried out by constructing the machine in a manner more fully hereinafter described and claimed and as shown in the drawings, wherein:—

30 Figure 1 is a vertical section of this machine complete.

Fig. 2 is a sectional detail on the line 2—2 of Fig. 1, and

35 Fig. 3 is a horizontal section on the line 3—3 thereof.

The casing of the machine comprises a hollow lower portion 1 which may be well called a standard, a hollow upper portion preferably cylindrical and which may well 40 be called the tub 2, and by preference a laterally offset independent housing 3 for the driving mechanism. The tub is open at the top and closed by a removable cover 4 whose flange 5 fits close into the mouth 6 of the 45 tub as shown in Fig. 1, and the body of the

cover has converging and preferably oblique air inlet openings or tubes 7 whose inner ends open through a disk 8 mounted within the chime as seen. The cover also has hoods 9 over the outer ends of the inlets 7, and the 55 inner ends of the hoods stand adjacent to a handle 10 or other device for raising the cover.

It will be understood that I prefer to employ gasoline or some other inflammable 60 agent for cleaning the clothes, and this liquid is admitted to the tub in any suitable way while the soiled liquid and sediment are drawn off through pipes 13 and 14 and a cock 15. The tub is raised at the center of 65 its bottom as shown at 16, and one of the outlet pipes may draw the contents from a point near the raised center. The latter carries a bearing 17 in which is rotatably and slidably mounted a main shaft. By 70 preference I provide a small chamber 18 at one side of the tub communicating with its interior, and at the top of the chamber is an outlet flue 19 leading to a chimney at a distant point and eventually out of the 75 building; and it will be understood that it is quite possible to apply a suction fan to this flue to withdraw the odors from the interior of the tub and create a draft through the inlet openings 7. I consider 80 this quite a desirable feature of my invention because it takes in fresh air from the room or apartment in which it is situated, rather than giving off odors and vapors, and therefore its offensiveness is reduced along 85 with the liability of accidental fire. The disk 8 serves to prevent splashing of the liquid gasoline or other inflammable cleanser within the tub, and every safeguard is thrown around the machine to avoid fire as 90 much as possible.

Disposed concentrically within the tub 2 is a basket 22 whose wall is perforated as seen and whose open upper end is surrounded by an inturned flange 21, and at its 95 center the bottom of this basket is raised as at 26 and supported upon a block 27 which in turn is mounted on the upper end of a main shaft 25. The latter passes downward through the bearing 17 and through 100

another bearing 29 within the standard or base 1, and in both of these bearings the shaft is capable of longitudinal reciprocation as well as of rotation. Manifestly 5 when it is raised it raises the basket as seen in dotted lines in Fig. 2 and when it is rotated it rotates the basket within the tub as will be set forth below. The shaft 25 carries a bevel gear 30 adapted, when the shaft 10 is raised, to be thrown into engagement with another bevel gear 31 on a second shaft 32 mounted in bearings 33 as seen, and by preference this last mentioned shaft has a sprocket 34 at its outer end within the 15 housing 3 connected by a chain belt 35 to a driving sprocket 36 fast on a shaft 37 having a crank handle 38 by which it may be rotated. When the shaft 25 is raised and the bevel gears thrown into mesh with 20 each other, the crank handle 38 may be rotated to cause the rotation of the basket within the tub; but when the shaft 25 is again dropped to the position shown in full lines in Fig. 2, the basket descends within 25 the tub and its rotation ceases.

While any appropriate means may be employed for raising and lowering the main shaft and the basket, I prefer to use a treadle 40 which is forked at its inner end 30 as shown at 41 and the fork arms pivoted as at 42 to opposite sides of a collar 43 which is mounted loosely on the shaft 25 below the bevel gear 30. When the outer end of the treadle is depressed, its inner 35 end is raised and the fork causes the rise of the collar and the rise of the collar raises the shaft in a manner which will be clear. The treadle is by preference supported on a link 44. For holding the treadle de- 40 pressed and the basket with its load of clothes raised, I preferably employ a toggle lever 45 as seen in Fig. 1. When now the toggle is straightened out as the treadle de- scends to the position shown in dotted lines 45 in Fig. 1, it will be obvious that the toggle will hold the treadle in this position until it is tripped by pressure on its central pivot in a manner which will be clear. Therefore, it is impossible for the basket to de- 50 scend accidentally into the liquid in the tub which, of course, would cause great agitation and splashing thereof.

I prefer to connect the gear 30 with the shaft 25 by some form of ratchet mechanism 55 which will permit the basket to rotate by momentum after it has been started by power, and in Fig. 2, I have given a cross sectional view on about the line 2—2 of Fig. 1. In this embodiment of the present idea 60 the shaft 25 has a pin 50 passing loosely through it, and the hub 51 of the bevel gear 30 has a socket 52 containing a spiral inner wall terminating in a shoulder 53 as shown. This form of ratchet mechanism

is one of many which may be employed 65 at this point. When the gears are thrown into engagement and power applied to the crank handle 38, the basket is rotated on its axis within the tub 2 and at the upper portion thereof and attains considerable 70 momentum. As soon as the power is cut off and even when the rotation of the gear 30 ceases, continued rotation of the basket and the shaft will be permitted by reason of the presence of this ratchet mechanism. How- 75 ever, I do not wish to be limited to the em- ployment of this detail, as other types of mechanism may be used at this point, or the same may be omitted entirely. In fact, it is quite possible to have the basket rotated 80 by power rather than by hand if desired.

In use, the gasoline or other cleaning liquid will be admitted to the tub 2 until it rises about to the dotted line in Fig. 1 with the parts having the proportions illus- 85 trated in the drawings. The cover is then removed and the clothing to be cleansed placed within the basket, the latter having been raised by depression of the foot piece of the treadle 40 as will be clear. The 90 basket is now lowered into the tub and raised and lowered as repeatedly as desired, especially if the cleaning agent employed should be water or the like, and of course the same may be hot or cold and it may be 95 changed as often as desired. Eventually, however, gasoline will doubtless be used to give the final cleaning to the clothes; and after having been dipped and thoroughly soaked in gasoline, depression of the foot 100 piece of the treadle 40 causes the rise of the main shaft and the basket until the clothes within the latter stand above the level of the gasoline within the tub. Now the gears 30 and 31 come in mesh and the power 105 mechanism may be actuated to rotate the basket so as to aerate the contents thereof, the fumes and vapors passing off through the flue 19 rather than through the inlet 7 in the cover, as suggested above. The latch 110 mechanism holds the toggle in position to keep the treadle depressed although the operator should take his foot off the same; and therefore he is free to reach into the basket when the cover is removed to agitate, 115 turn over, and eventually withdraw the clothing, and in fact pass entirely around the machine, at will. After the first batch of clothing has been cleansed it is removed and a second charge substituted therefor 120 and cleansed in the same manner.

What is claimed is:—

In a washing machine of the class de- 125 scribed, the combination with a tub hav- ing a bearing at the center of its bottom; of a shaft slidably and rotatably mounted through said bearing, a perforated basket carried by the upper end of said shaft with-

in the tub, means for raising and lowering said shaft at will, a bevel gear fast on the shaft below the basket, a driving shaft having a bevel gear adapted to be engaged with the gear named when the basket is raised, and mechanism for rotating the last-mentioned bevel gear at will.

In testimony whereof I affix my signature in presence of two witnesses.

WILLARD S. LILLIBRIDGE.
